(57) **CLAIM**

The ornamental design for a foot care apparatus, as shown and described.

DESCRIPTION

FIG. 1 is a front top left side perspective view of a foot care apparatus showing my new design;
 FIG. 2 is a front top right side perspective view thereof;
 FIG. 3 is a rear top right side perspective view thereof;
 FIG. 4 is a rear top left side perspective view thereof;
 FIG. 5 is a rear bottom right side perspective view thereof;
 FIG. 6 is a rear bottom left side perspective view thereof;
 FIG. 7 is a front elevational view thereof;
 FIG. 8 is a rear elevational view thereof;
 FIG. 9 is a top plan view thereof;
 FIG. 10 is a bottom plan view thereof;
 FIG. 11 is a right side elevational view thereof; and,
 FIG. 12 is a left side elevational view thereof.
